UNITED STATES PATENT OFFICE.

GIUSEPPE REGONDI, OF NEW BRIGHTON, NEW YORK.

MUSIC-LEAF TURNER.

No. 845,895.

Specification of Letters Patent.

Patented March 5, 1907.

Application filed March 8, 1906. Serial No. 304,978.

To all whom it may concern:

Be it known that I, GIUSEPPE REGONDI, a subject of the King of Italy, residing at New Brighton, in the county of Richmond, State of New York, have invented certain new and useful Improvements in Music-Leaf Turners, of which the following is a specification.

This invention relates to music-leaf turners.

10 It has for an object to improve the mechanism for intermittently rotating a drum that controls the swinging movement of a plurality of leaf-turning arms.

15 A further object is to provide a device for holding the sheet-music to the support during the turning of the leaves, the device having means for holding it away from the sheet-music to permit the latter to be introduced to and removed from the support.

20 Other and still further objects will appear in the following description and will be more particularly pointed out in the appended claims.

25 In the drawings, Figure 1 is a front elevation of a piano employing my invention. Fig. 2 is an inside view of the front board of the piano, with the casing supporting the drum in section, the other parts being in elevation. Fig. 3 is a horizontal section on the

30 line 3 3 of Fig. 2 through the casing when applied to the front board of a piano on line 3 3, Fig. 2, the other parts of the invention being shown in top plan. Fig. 4 is a bottom plan view of the drum and the operating-dogs on line 4 4, Fig. 2. Fig. 5 is a section on line 5 5 of Fig. 2. Fig. 6 is a section of a piano, showing another embodiment of connecting the treadles to the drum-operating mechanism.

35 Fig. 7 is a view of a music-stand with my invention applied thereto. Fig. 8 is a side elevation of the sheet-music holder. Fig. 9 is a detached perspective of the sheet-music holder. Fig. 10 is a detail view of the treadle. Fig. 11 is a detail view of one of the clips.

40 Referring more particularly to the drawings, 1 indicates a series of arms all of the same length, formed of thin material and having paper-clips 2 of lyre form, slidable thereon to engage the leaves of sheet-music or the like. By making them slidable on the arms I am enabled to engage leaves of various widths. There may be provided any suitable number of these arms 1. In the drawing I have shown six. Each arm is rigidly connected to a small pinion 3, which is loosely journaled on a vertical shaft 4, mount-

ed in a casing 5. This casing may be supported on the rear face of the front board of a piano directly above the sheet-music holder 6, as shown in Figs. 1 to 6, or on the rear of a 60 music-stand, as shown in Fig. 7. In either case the pinions 3 project to the outside through an opening 7. Within the casing 5 is journaled a vertical shaft 8, which carries a drum 9, provided with a plurality of segmental racks 10, arranged in stepped relation. These racks each have a number of teeth equal to one-half of the teeth on one of the pinions 3 and are adapted to successively engage successive pinions 3 and rotate the 70 same one hundred and eighty degrees to swing one of the arms 1.

To rotate the drum 9 in opposite directions, I provide a pair of toothed wheels 11 and 12 one above the other, the lower one, 75 12, being of less diameter than the upper one—i. e., the crown of its teeth extending to the base of the teeth of the upper one. The teeth of each wheel are the same in number as the racks on the drum, and each have one 80 inclined face 13 and a straight or radial face 14, the inclined face 15 between the two teeth on each wheel being longer than the other inclined faces. These two teeth are the teeth producing the first and last rotation, and the lengthened inclined face is to prevent any further rotation of the drum in the same direction after all the leaf-arms have been swung in one direction, thus preventing the breaking of any parts. 90

The teeth of the wheels 11 and 12 have their inclined faces extending in opposite directions and are engaged by a pair of pivoted L-shaped dogs 16 and 17. Each dog has its upper end adapted, when rotated in one direction, to engage a straight face 14 and cause the drum to rotate with the dog and when rotated in the other direction to ride on an inclined face 13 to the next straight face. The lower end of each dog is pivoted at 18 to one of two arms 19, loosely journaled on the shaft 8 and having a spiral spring 20, tending to hold it in one position. Both dogs are held elevated by springs 18^a. 95

To rotate one arm from the position in 105 which its spring 20 tends to hold it and at the same time to remove the dog on the other arm from its toothed wheel, I provide the following means: Each arm 19 has connected to its end one end of a cable 21, which after passing around a roller 28 is connected at its other end to the lower end of a vertical slide 110

22, held in an elevated position by a spring 23. Each slide 22 is mounted on the front wall of the piano and has a horizontal portion 23^a to throw its upper end in the vertical plane of the dog which it is to operate, the upper ends being extended horizontally at 24 to lie over the dogs. Each cable 21 passes through an eye 25 on one end of a horizontal slide 26, which is moved by a spring 27 in the direction to slacken the cable. To the opposite end of each horizontal slide 26 is connected a cable 29, which may be operated in any suitable manner. In Fig. 1 I have shown each cable 29 leading to and around a pulley 30, located inside and near one end of the piano, thence downwardly to a pulley 31, located near the bottom of the piano, and from the pulley 31 to and around a pulley 32, located near the middle of the piano. The cable is then connected with a treadle 33.

In the embodiment shown in Fig. 6 each cable 29 leads to the upper end of a bell-crank lever 34, pivoted on the inside of the end wall of the piano. To the other end of each bell-crank lever 34 is connected a reciprocating rod 35, which is connected by a pivoted lever to a treadle 36.

It is obvious that as soon as either cable 29 is pulled by depressing one of the treadles of either embodiment a slide 26 will cause both ends of one cable 21 to be pulled, and as this cable is connected to both dogs 16 and 17 one dog will be pulled out of engagement with its toothed wheel and the other dog will be caused to swing and rotate the drum 9 in one direction. If the other cable 29 is pulled, a reverse rotation of the drum 9 will take place. The dog causing the rotation moves the drum the distance of one of the racks 10 only. Of course when the drum is rotated in one direction the leaf-arms 1 swing in one direction, and vice versa.

In Fig. 7 I have shown my invention applied to a music-stand. In this embodiment the cables 29 lead from the treadles 33 to the slides 26, arranged on the back of the stand in the same manner as in the other embodiment.

The treadles 33 may be formed in any suitable manner; but I prefer to construct them as shown in Fig. 10.

A pair of side members 37, each formed of a strip of metal bent upwardly upon itself, as at 38, to form a bearing for a shaft 39, carrying the foot-piece, is provided, the side members being provided with eyes 40 at their end, by which they are secured in place, and being connected together by a bar 41, on which roller 32 is journaled.

To hold the music while the leaves are being turned, and thus to prevent their being thrown to the floor during the operation of the turner, I provide the device shown in detail in Figs. 8 and 9. It comprises a thin flexible arm 41', adapted to fit between the

leaves at the point of their connection, and which is normally pressed against the sheets of music. The arm 41' is carried by a block 42, pivoted at 43 between two arms 44 on a plate 45, which is attached to the rear face of the front board of the piano or to the rear face of the music-stand, the support 46 being slotted or cut away at 47 to permit the free movement of the arm to and from the sheet-music. To hold the arm against the sheet-music, a coil-spring 48 is provided and abuts at one end against a shoulder 49 on the block 42 and at its other end against a shoulder 50 on plate 45, projections 51 entering the ends of the spring and holding it against lateral displacement.

The arm 41' is held away from the sheet-music by providing a laterally-swinging portion 52, which is in the form of a knob pivoted at 53 and adapted to be thrown into a notch 54 on one of the arms 44 on the attaching-plate 45 when the arm 41' is out of engagement with the sheet-music, as shown in dotted lines in Fig. 8.

Having thus described my invention, what I claim is—

1. The combination with leaf-turning arms and a rotatable drum causing the rotation of said arms, of a pair of toothed wheels rotating with said drum, a dog for rotating each toothed wheel, a pair of treadles, and connection from each treadle to one dog to cause the rotation of the drum, and to the other dog to throw it out of engagement with its toothed wheel, the connection being such that each treadle rotates a different dog.

2. The combination with leaf-turning arms, and a rotatable drum for causing the swinging of said arms, of a pair of toothed wheels rotating with said drum, a pair of hinged and swinging dogs, each adapted to engage a toothed wheel, a pair of devices under control of an operator, and connection from each device to one dog to swing it and to the other dog to move it on its hinge out of engagement with its toothed wheel, the connection being such that each device swings a different dog.

3. The combination with leaf-turning arms, of a rotatable drum connected with said arms, a pair of dogs controlling said drum, a pair of slides, connection from each slide to one dog for rotating the drum and to the other dog to throw it to an inoperative position, the connection of each slide being such that each slide rotates a different dog, and means for moving the slides.

4. The combination with leaf-turning arms, of a rotatable drum connected with said arms, a pair of toothed wheels turning with said drum, a pair of swinging arms loosely journaled on the shaft of the drum, a pair of dogs each hinged to one of the swinging arms, and adapted to engage one of the toothed wheels, a pair of devices under control of an

operator, and connection from each device to one of the swinging arms to cause the dog and the drum to rotate and to the dog on the other arm to throw it out of engagement 5 with its toothed wheel, the connections being such that each device swings a different arm and throws a different dog out of engagement.

5. The combination with the leaf-turning arms, of a rotatable drum connected with said arms, a pair of toothed wheels turning with said drum, a pair of swinging arms loosely journaled on the shaft of the drum, a pair of dogs each hinged to one of the swinging arms and adapted to engage one of the toothed 15 wheels, a pair of slides under control of an operator, a pair of devices each arranged to engage one of the pivoted dogs, and a pair of cables each connected at one end to a swinging arm, loosely connected between its ends 20 to a slide and connected at its other end to the device arranged to engage the other dog, each cable connecting the slides and the dogs so that each slide swings a different arm and operates a different dog on its hinge.

25. 6. The combination with leaf-turning arms, of a rotatable drum connected with said arms, a pair of toothed wheels turning with said drum, a pair of swinging arms loosely journaled on the shaft of the drum, a pair of 30 springs each tending to move one arm in one direction, a pair of L-shaped dogs, each pivoted to one of the swinging arms at one end and engaging a toothed wheel at its other end, a pair of slides each having a portion disposed over one of the dogs, a pair of springs 35 holding said slides away from the dogs, a

pair of cables each connected at its ends to the swinging arm of one dog and the slide of the other dog, and a pair of slides under the control of an operator, each connected to a 40 cable intermediate its ends, so that each of said last-named slides swings a different arm and operates a different first-named slide disposed over a dog.

7. The combination with leaf-turning arms, 45 of a rotatable drum causing the operation of said arms, a pair of dogs controlling the rotation of the drum, a pair of devices under the control of an operator and connections from each device to one dog to cause it to rotate 50 the drum, and to the other dog to make it inoperative, the connections being such that each device rotates the drum by a different dog.

8. The combination with leaf-turning arms, 55 of a rotatable drum causing the operation of said arms, a pair of rotatable dogs controlling the rotation of the drum, a pair of slides under the control of an operator, and a pair of cables each connecting one dog and one 60 slide to cause the rotation of the drum, and the other dog and the same slide to make said dog inoperative, the cables being so connected that each device rotates the drum by 65 a different dog.

The foregoing specification signed at New Brighton, New York, this 20th day of February, 1906.

GIUSEPPE REGONDI.

In presence of—

WILLIAM R. CORSON,
FRANK J. MULLEGAN.
